UNITED STATES PATENT OFFICE

FELIX J. HEBERT, OF PORT ARTHUR, TEXAS

AUTOMATIC COASTER

Application filed October 26, 1929. Serial No. 402,742.

This invention relates to mechanical toys and has as its primary object the provision of a mechanical toy wherein a car will run by gravity down an inclined loop track together with means for automatically raising the car from the bottom of the track to the top of the latter so that the car may again repeat its performance.

A still further object of the invention is to provide a mechanical toy embodying an inclined loop track, an elevator positioned intermediate the ends of the track together with means controllable by a car traveling by gravity on the track for actuating the elevator, in such a manner that when the car runs from the bottom of the track or to the elevator the elevator will be automatically operated to raise the car to the upper end of the track to be discharged therefrom on the track, said elevator remaining in its raised position until the car has traveled a predetermined distance on the track, whereby means controllable by the car will release the elevator to permit a descent of the elevator so that the elevator will be at the lowermost end of the track in ample time for receiving the car thereon after it has completed its travel around the track.

A still further object of this invention is to provide a mechanical toy of the character above mentioned, which is comparatively simple in construction, will afford amusement to young and old alike, will be inexpensive, and which may be readily transported from place to place.

Other objects and advantages of the invention will become apparent during a study of the following description, taken in connection with the accompanying drawing, wherein:

Figure 1 is a top plan view of the mechanical toy embodying the features of my invention.

Figure 2 is a side elevation thereof.

Figure 3 is a fragmentary detail view looking at one side of the elevator disposed between the ends of the track.

Figure 4 is a side elevation of the mechanism for raising and lowering the elevator.

Figure 5 is a fragmentary detail view part-

ly in section and partly in elevation for more fully illustrating a clutch mechanism embodying one of the features of this invention.

Figure 6 is a side elevation of the control disc.

55

Figure 7 is a perspective view of the release lever for controlling the control disc.

With reference more in detail to the drawings, it will be seen that my mechanical toy comprises a circular base or platform 5 and inclined looped track 6 mounted on the upper end of supports 7 suitably secured to and rising from the base or platform 5. As shown to advantage in Figure 3, between the adjacent end of the track 6 and supported on the platform 5 is a suitable elevator structure designated generally by the reference character E.

The elevator structure E comprises four posts or uprights 8, the lower ends of which posts are receivable in sprockets 9 rising from the base 5. These posts 8 are of a height to extend a suitable distance beyond the upper or higher end of the track 6, and a cover plate 10 at each corner thereof is secured to each of the posts 8 as at 11. The elevator per se consists of a track section 12, which section of track 12 is of a length substantially equal to the distance between the ends of the track 6. On each side of the rails of the track section 6, and adjacent the ends of the rails, the said rails of the track section 12 have secured thereto in any desired manner vertical sleeves 13, there being one sleeve 13 for each upright or post 8, and the sleeves 13 are slidable on the respective posts 8. It is preferable, that the sleeves 13 be so fixed at the ends of the track section 12 that the track section will be disposed at a suitable incline, the incline being in the same general direction as the incline of the track 6 as will become apparent from a study of Figure 3.

The elevator member is designated generally by the reference character 14 and this elevator member 14 is in the nature of a suitable frame, through which the track section 12 extends, the intermediate portion of the track section resting on the lower cross bar 15 of said elevator frame. Secured to the upper cross bar of the frame 14 or elevator

as it may be termed, is one end of a cable as at 16. The cable is designated by the reference character 17, and this cable is trained over a pulley 18 rotatably mounted in a suitable bracket 19 fastened to the top plate 10. The cable 17 then extends downwardly and is adapted to be wound upon a drum 20 the other end of the cable being anchored to the drum as at 21. The manner of mounting and 10 the operation of this drum will be hereinafter more fully set forth.

Arranged on the platform 5 and within the confines of the track 6, and suitably secured to and rising from the base is a pair 15 of spaced parallel plates 22. These plates 22 rise vertically from the base 5 and a relatively short shaft 23 is rotatably supported between the plates 22 adjacent one end of the plates. Disposed about the shaft 23 between the plates 22 is a band spring 24, one 20 end of which band spring 24 is anchored to the shaft 23 and the other end anchored as at 25 to a cross-bar 26 connecting the upper portion of the plates 22 adjacent said one end of the plates. Also mounted on the shaft 23 between the spring 24 and one of the plates 22 and adapted for rotation with said shaft is a relatively large gear wheel 27. The shaft 23 is also provided to one side of the 25 gear wheel 27 with a ratchet wheel 28 also adapted to rotate with the shaft and a dog 28' is pivoted on an adjacent side of the gear wheel 27 for engagement with the teeth of the ratchet wheel 28. A suitable spring 29 is anchored at one end to an adjacent side of the wheel 27 and the free end of the spring bears against the dog 28' for maintaining the free end of the dog in engagement with the teeth of the ratchet wheel shown to advantage in Figure 4. On one end thereof the shaft 23 may be squared or otherwise formed as at 30 whereby a key or other actuating element may be operatively associated with said one end of the shaft for rotating the shaft in one direction against the action of the spring 24.

A second horizontally disposed shaft 31 has one end thereof extending through a suitable opening formed in one of the plates 22, said one end of the shaft extending between said plates and the other end of the shaft is mounted in a suitable bearing 32 formed on the upper end of a bearing standard or bracket 33. This bracket 33 is mounted on the platform 5 and is disposed in spaced relation to said one plate 22. The said drum 20, hereinbefore referred to, is rotatably and slidably mounted on a reduced portion 31' of the shaft 31 as shown to advantage in Figure 5. The drum 20 has one end thereof adapted to abut the shoulder 34 formed on the shaft 31, while the hub 20' of said drum 20 at the opposite end of the drum has an extended portion 35 which extended portion

merges into an outstanding flange 36 on the outer end thereof.

In order that the drum 20 may be readily and operatively associated with the shaft 31 for rotation with the shaft I provide a novel clutch mechanism embodying an angle bar 37 having one flange thereof secured to one end of the drum 20 by welding or in any other desired manner, the other flange of the angle bar 37 extending outwardly from said one end of the drum and constituting a stop adapted to engage an abutment 38, which abutment 38 is in the nature of an arm extending laterally from the shaft 31 adjacent the reduced end of the shaft as shown to advantage in Figure 5.

It will be apparent that the abutment arm of the angle bracket 37 will only engage with the stop arm 38 of the shaft 31 when that end of the drum is disposed against the shoulder 34 of said shaft 31, or when the drum is in that position shown in Figure 5. The other element of my improved clutch mechanism embodies means for moving the drum axially of the shaft 31 so that said one end of the drum will abut the shoulder 34. This element of the clutch mechanism embodies a substantially V-shaped frame 39 to the end of which frame 39 is secured a disc or collar 40 slidable on the reduced end of the shaft 31 between the bearing 32 and the flanged end 36 of the hub 20' of the drum. For normally urging the collar 40 against the flange 36 there is provided a retractile coil spring 41, one end of which is anchored to the apex of the frame 39 while the other end is anchored as at 42 to the bearing portion 32 of the bearing standard 33 as shown to advantage in Figure 5.

Rotative power for the shaft 31 is derived from the fact that the shaft 31 on that end thereof disposed between the plates 22-22 is formed with a pinion 43 in mesh with the gear wheel 27 so that obviously rotation of the shaft 31 caused in the well known manner by the unwinding of the spring 24 will impart rotation to said shaft 31. On its extreme end, and adjacent the pinion 43 said shaft 31 has secured thereto for rotation therewith a relatively large control disc 44. This disc 44 has provided at one point on its periphery a notch 45.

To lock the shaft 31 against rotation imparted thereto from rotation of the shaft 23, I provide a control lever designated generally by the reference character 44. This control lever 44 is substantially of U-shape configuration and has the crown portion thereof adjacent its extremity rockably mounted in suitable brackets 45 secured to the base 5. One leg 46 of the U-shape control lever 44 is adapted for disposition adjacent the elevator structure E and at the forward end of the track section 12 as shown to advantage in Figure 3. The other leg 47 of said

control bracket is disposed adjacent one plate 22, and this last mentioned leg 47 terminates in a lateral projection 48 extending at right angles to the crown of the U-shaped lever 44 as shown to advantage in Figure 7. This extension 48 is adapted to be received in the notch 45 of the disc 44 so that manifestly when said projection or extension 48 is in the notch 45 rotation of the disc 44 is prevented, resulting in the maintaining of the shaft 31 against rotation. For normally maintaining the locking member 48 in the notch 45 of the disc 44 I provide a coil spring 49 anchored at one end to the leg 46 and having its opposite end suitably anchored as at 50 to the platform 5.

It being assumed, that the shaft 23 when the suitable application of a key or other actuating medium applied thereto has been manually rotated in one direction for winding the spring 24 to a taut condition and a suitable car designated generally by the reference character B and of sufficient weight has traveled down the incline 6, and then the elevator member 14 is in a lowered position so that the track section 12 is in alignment with the lower end of the track 6, and the member or projection 48 is in the notch 45 of the control disc 44, the said car B at its completion of travel will run onto the track section 12 with sufficient force to strike against the leg 46 of the control or operating member 44 for rocking the member 44 thus releasing or withdrawing the projection 48 from its notch 45 with the result that the shaft 23 under action of the spring 24 will rotate in an opposite direction and through the medium of the gear 27 meshing with the pinion 43 rotates the shaft 31, which in turn will revolve or rotate the drum 20, the L-shaped member 37 having its lateral flange engaging the arm 38 of said shaft 31 and maintained in said engagement through the medium of the collar 40 urged against the flanged end 36 of the hub 20 through the medium of the spring 41 acting upon the frame 39 whereupon, the cable 17 will wind upon the revolving drum thus raising the elevator 14 and with the elevator 14 the track section 12 and car B now resting on said track section, the track section 12 now being raised to move into alignment with the upper raised end of the track A. Manifestly, due to the inclination of the track section 12 the car by gravity will roll therefrom and on to the track 6 to travel by gravity down said track 6. The car B now travels down the track 6 and at a point intermediate the ends of the track will engage with the upper end of a crank arm 49 disposed at a point adjacent one side of the track 6 about diametrically opposite the elevator E. The car thus striking against the upper end of the crank arm 49 will rock the crank shaft 50 thereof which crank shaft 50 is rockably

mounted in suitably bearing 51 anchored to the base 5 as shown to advantage in Figure 2. At its other end, the crank shaft 50 is provided with a crank arm 52 which crank arm 52 has an operable connection 53 with the extended end portion 35 of the drum 25 as shown to advantage in Figure 1. Obviously, this striking of the crank arm 49 by the car B will rock the shaft 50 in one direction so that through the medium of the operable connection 53 with the hub of the drum 20 slide the drum upon the reduced end of the shaft 31 thus disengaging the lateral flange or arm of the L-shaped brackets 37 with the stop arm 38 of the shaft 31 whereupon the drum 20 will be enabled to rotate on the shaft 31 free of connection with the shaft. This obviously will result in an unwinding of the cable 17 upon the drum 20 which unwinding of the cable will be caused by the weight of the track section 12 mounted in the elevator frame 14, so that said track section 12 will be lowered to move into alignment with the lower end of the track 6 in sufficient time to permit the car B at the terminal of its travel on the track 6 to run on to the track section 12. Obviously, when during the raising of the elevator, the car B is brought out of engagement with the arm 46 of the lever 44, said lever will have been rocked through the medium of the spring 49 for again placing the projection 48 of the leg 47 into the notch 45 of said disc 44, the disc having completed one full revolution as have also the shafts 23 and 31. This full complete revolution of the disk and shaft will require about the same amount of time as is required for the car to travel from one end to the other of the track, so that completion of this one revolution will take place at about the same time the car B traveling on the track 6 has come into contact with the crank arm 49 of the crank shaft 50. This being the case, apparently when the car B again moves onto the lowered track section 12, the said car B will again strike the arm 46 and the operation again repeated.

It is preferable, in order to prevent the car B from running off the end of the track section 12 to provide a stop in the nature of a post 55 rising from the platform 5 up to the upper raised end of the track 6 between the rails of the track as shown to advantage in Figure 1.

It is believed that from the foregoing description, taken in connection with the accompanying drawings, a clear understanding of the operation and construction, utility and amusement derived by young and old from a mechanical toy of this nature will be had. A more detailed description thereof is therefore deemed unnecessary.

Even though I have herein shown and described the preferred embodiment of my

invention, it is to be understood that the same is susceptible to certain changes in size, shape and the materials used and in the rearrangement of the several elements comprising the invention as fall within the scope of the spirit of the invention as herein described and of the claims forming a part of this specification.

Having thus described my invention, what I wish to claim as new is:—

1. In a mechanical toy of the class described, the combination of an inclined track, and a car running thereon, a vertically slideable elevator adapted to receive the car, and means for actuating said elevator, and means controllable by the momentum of the car for releasing the first mentioned means whereby said elevator may be alternately moved to both raised and lowered position.

2. In a toy of the class described, an inclined track, a car adapted to travel by gravity over said track, a vertically slideable car receiving elevator mounted between the adjacent ends of said track, said elevator adapted to be normally disposed and retained in a lowered position through the medium of its own weight, means for actuating said elevator for moving said elevator to a raised position, and means actuatable upon the passing of said car from said track to said elevator for releasing the first mentioned means whereby said elevator will be moved to a raised position.

3. In a toy of the class described, an inclined track, a car adapted to travel by gravity over said track, a vertically slideable car receiving elevator mounted between the adjacent ends of said track, said elevator adapted to be normally disposed and retained in a lowered position through the medium of its own weight, means for actuating said elevator for moving said elevator to a raised position, and means actuatable upon the passing of said car from said track to said elevator for releasing the first mentioned means whereby said elevator will be moved to a raised position, means for maintaining said car on said elevator during the upward travel of said elevator, and means on said elevator whereby when said elevator has reached the raised end of said track said car will move by gravity from said elevator onto the said track.

4. In a toy of the class described, an inclined track, a car adapted to travel by gravity over said track, a vertically slideable car receiving elevator mounted between the adjacent ends of said track, said elevator adapted to be normally disposed and retained in a lowered position through the medium of its own weight, means for actuating said elevator for moving said elevator to a raised position, and means actuatable upon the passing of said car from said track to said elevator for releasing the first mentioned means whereby

said elevator will be moved to a raised position, means for maintaining said car on said elevator during the upward travel of said elevator, and means on said elevator whereby when said elevator has reached the raised end of said track said car will move by gravity from said elevator onto the said track, and means for maintaining said elevator in a raised position.

5. In a toy of the class described, an inclined track, a car adapted to travel by gravity over said track, a vertically slideable car receiving elevator mounted between the adjacent ends of said track, said elevator adapted to be normally disposed and retained in a lowered position through the medium of its own weight, means for actuating said elevator for moving said elevator to a raised position, and means actuatable upon the passing of said car from said track to said elevator for releasing the first mentioned means whereby said elevator will be moved to a raised position, means for maintaining said car on said elevator during the upward travel of said elevator, and means on said elevator whereby when said elevator has reached the raised end of said track said car will move by gravity from said elevator onto the said track, and means for maintaining said elevator in a raised position, and means controllable by the car in the path of movement of said car over said track for releasing said elevator retaining means, whereby said elevator may be moved to a lowered position for receiving said car at the completion of its travel over said track.

6. In a toy of the class described, an inclined track, a car adapted to travel over said track, a vertically slideable track section arranged between adjacent ends of the first mentioned track and adapted to receive said car upon completion of its travel over said first mentioned track for raising said car to its initial position of travel on said track, means for slidably mounting said track section at an incline, means for raising said track section, means for retaining said track section in an elevated position, means for releasing said first mentioned means when said car is received on said track section, and means actuatable by said car at a certain point of travel on said track whereby said track section may be released from its elevated position to return under its own weight to its lowermost position.

7. In a mechanical toy of the class described, an inclined track, a car adapted to travel over said track, a vertically slideable inclined track section, a rotatably supported shaft, mechanism for rotating said shaft, a drum slidably and rotatably mounted on the shaft, a cable wound on said drum and having operating connection with said vertically slideable track section, means for locking the shaft in a non-rotative position against the

action of said mechanism, said last mentioned means including means engageable by the car upon transfer of the car from said inclined track to said track section whereby said shaft will be actuated to be rotated by said mechanism, and means carried by said shaft and engageable with said drum for imparting rotation to said drum to move said track section to an elevated position.

8. In a mechanical toy of the class described, an inclined track, a car adapted to travel over said track, a vertically slidable inclined track section, a rotatably supported shaft, mechanism for rotating said shaft, a drum slidably and rotatably mounted on the shaft, a cable wound on said drum and having operating connection with said vertically slidable track section, means for locking the shaft in a non-rotative position against the action of said mechanism, said last mentioned means including means engageable by the car upon transfer of the car from said inclined track to said track section whereby said shaft will be actuated to be rotated by said mechanism, and means carried by said shaft and engageable with said drum for imparting rotation to said drum to move said track section to an elevated position, spring means for normally returning said retaining means in locked engagement with said shaft when said shaft has completed one revolution.

9. In a mechanical toy of the class described, an inclined track, a car adapted to travel over said track, a vertically slidable inclined track section, a rotatably supported shaft, mechanism for rotating said shaft, a drum slidably and rotatably mounted on the shaft, a cable wound on said drum and having operating connection with said vertically slidable track section, means for locking the shaft in a non-rotative position against the action of said mechanism, said last mentioned means including means engageable by the car upon transfer of the car from said inclined track to said track section whereby said shaft will be actuated to be rotated by said mechanism, and means carried by said shaft and engageable with said drum for imparting rotation to said drum to move said track section to an elevated position, spring means for normally returning said retaining means in locked engagement with said shaft when said shaft has completed one revolution, and means controllable by said car at a predetermined point of travel of said car on said track for releasing said drum whereby said drum may rotate freely on said shaft under the control of the weight of said track section, whereby said track section may be moved to a lower position.

10. In a mechanical toy of the class described, an inclined track, a car adapted to travel over said track, a vertically slidable inclined track section, a rotatably supported shaft, mechanism for rotating said shaft, a

drum slidably and rotatably mounted on the shaft, a cable wound on said drum and having operating connection with said vertically slidable track section, means for locking the shaft in a non-rotative position against the action of said mechanism, said last mentioned means including means engageable by the car upon transfer of the car from said inclined track to said track section whereby said shaft will be actuated to be rotated by said mechanism, and means carried by said shaft and engageable with said drum for imparting rotation to said drum to move said track section to an elevated position, 70 spring means for normally returning said retaining means in locked engagement with said shaft when said shaft has completed one revolution, and means controllable by said car at a predetermined point of travel of said car on said track for releasing said drum whereby said drum may rotate freely on said shaft under the control of the weight of said track section, whereby said track section may be moved to a lower position, said last mentioned means including a rock shaft, means operatively connecting said rock shaft with said drum, said rock shaft having a crank arm disposed thereon and adjacent said track.

In testimony whereof I affix my signature.
